Primary Examiner — April Rivas(74) Attorney, Agent, or Firm — KA Filing LLC; Wayne V. Harper; Cynthia Flanigan(57) CLAIM

I claim the ornamental design for a cosmetic case, as shown and described.

DESCRIPTION

FIG. 1 is a Perspective view of a cosmetic case showing my new design;

FIG. 2 is a Front view of the cosmetic case as shown in FIG. 1;

FIG. 3 is a Back view of the cosmetic case as shown in FIG. 1;

FIG. 4 is a Left-side view of the cosmetic case as shown in FIG. 1;

FIG. 5 is a Right-side view of the cosmetic case as shown in FIG. 1;

FIG. 6 is a Top view of the cosmetic case as shown in FIG. 1;

FIG. 7 is a Bottom view of the cosmetic case as shown in FIG. 1; and,

FIG. 8 is a Closed Perspective view of the cosmetic case as shown in FIG. 1.

The broken lines illustrate portions of the cosmetic case and form no part of the claimed design.
